UNITED STATES PATENT OFFICE.

ANTONIO DI DOMENICA AND ANTONINO AMICARELLI, OF WALLINGFORD, CONNECTICUT, ASSIGNORS TO THE NEW ENGLAND MACARONI COMPANY, OF NEW HAVEN, CONNECTICUT, A CORPORATION OF CONNECTICUT.

DRIER.

1,086,903.

Specification of Letters Patent. Patented Feb. 10, 1914.

Application filed July 11, 1913. Serial No. 778,544.

To all whom it may concern:

Be it known that we, ANTONIO DI DOMENICA and ANTONINO AMICARELLI, subjects of Victor Immanuel III, King of Italy, residing at Wallingford, in the county of New Haven and State of Connecticut, have invented certain new and useful Improvements in Driers, of which the following is a specification, reference being had therein to the accompanying drawings.

Our invention relates to a new and improved drier, and refers more particularly to the type of drier used for drying macaroni.

It is the object of our invention, among other things, to construct the drier so as to provide several sections into which air at the atmospheric humidity may be caused to enter therein and circulate therethrough, means of accelerating the movement of the air within the drier by the action of one or more fans, to provide means whereby the humidity of the air within the drier may be controlled by one or more ports having an indirect connection with the outer air, and finally to so design the drier that it will be simple in its operation and of such few parts that they may be economically constructed and readily assembled.

To these, and other ends, our invention consists in the drier, having certain details of construction and combinations of parts, which will be hereinafter described and more particularly pointed out in the claims.

Referring to the drawings, in which like numerals of reference designate like parts in the several figures; Figure 1 is an elevation of our improved drier complete; Fig. 2 is a transverse sectional view thereof; Fig. 3 is a plan view; and Fig. 4 is a fragmentary plan view, taken upon line A—B of Fig. 2.

In the practice of our invention, we provide a four sided body member 1, preferably made of matched sheathing, having a top 2 and suitable bracing timbers 3—3, to which the sheathing is secured.

In each side of the body member is an opening 4 that extends substantially across one-half of the width thereof, and in front of which is a sliding door 5, which slides upon a track 6 and is suspended upon a rail 7 by one or more hangers 8.

Within the body member, and at a point

slightly above the bottom thereof, are the floor bars 9, and connected therewith are a plurality of floor strips 10, which are arranged an equal distance apart, and between which are hinged the valve strips 11. These strips, when in their down or closed position, completely fill the open space between the strips 10, and form a smooth, unbroken floor for the drying chambers. The valve strips 11 are moved from their open to their closed position through a bar 12 that is operated and supported at one end by a lever 13, and at the other end by a link 14, the lever 13 and link 14 being pivotally secured at their lower ends to the blocks 15. Between each of the valve strips 11 and the bar 12, is a link 16 that forms a positive connection therebetween. As the lever 13 is rocked upon its pivot mounting, the bar 12 has a movement in the direction of its length, and also a slightly vertical movement, which latter movement is imparted to the valve strips 11 through the links 16, causing the valve strips to move upon their hinged connection, with the strips 10, and open and close the spaces therebetween. The air that passes from the drier chamber through the said open spaces collects in the chamber 17 beneath the bars 9, and escapes therefrom, when desired, through one or more openings in the side thereof, said openings being covered by vertically movable slides 18 upon the outside of the body member. Each side of the body member is provided with one of these slides, they being preferably arranged beneath the openings 4, so that no two of these openings are in a direct line with the other. As these slides, and their method of operation, are common and well known, we have not therefore described them herein in detail.

Within the interior of the drier are a plurality of supporting racks, arranged one above the other, and constructed with a horizontal bar 20 and a brace 19 to support the inner end thereof. Within the interior of the drier, adjacent to each side thereof, and upon the same line as the horizontal bars 20, are the supporting bars 21. As shown in the drawings, the racks above referred to are four in number, one being provided for each of the separate sections within the drier, and at the inner end they support a tube 22 by means of the collars

23 that surround and are secured to said tube and projecting over the inner end of said bars 20, as shown in Fig. 2.

To load the drier, the valve strips 11 are moved to their down position, so that the top thereof is flush with the top of the strips 10, the door 5 is moved so as to uncover the opening 4 through the body member, and the macaroni, in a moist condition, suspended in strips over a rod 24, is carried into the drier, and the rod placed so that one end is supported by the horizontal bar 20, and the other end by the bar 21. A plurality of said rods, when in their relative positions in the drier, being shown by broken lines in Fig. 4. Two layers of macaroni are placed in each section of the drier, one above the other, after which the door 5 is returned to its closed position.

20 Air is drawn into the drier from the outside of the body member through an opening 25 in the top 2, and caused to circulate within the drier through the action of one or more fans 26, which are fixed to a shaft 27 that passes through the opening 25, tube 22, being supported at its lower end in a block 28, and at its upper end in a swivel bearing 34 mounted in the brackets 35 fixed to the top 2. The blades of the fans and 25 direction of rotation are such that the air is drawn in through the opening 25 and driven downwardly through the damp macaroni.

The shaft 27 is rotated in any convenient manner, the means herein shown being a shaft 28 that is supported in journals 29 upon the top 2, and driven by a belt 30, a pulley 31 upon said shaft and a pulley 32 upon the shaft 27, said pulleys being connected by a belt 33.

If it is desired to admit more air into the drier than will pass through the opening 25, means are provided for this purpose, said means comprising an opening 36, 45 through the top 2, at a point directly over each one of the four sections in the drier that is surrounded by a flange 37, to which is hinged a valve 38 and connecting said valves, in pairs, are the cords 39, which are 50 connected by a cord 40. As the cord 40 is pulled, the valves 38 are lifted off their seat, so as to admit air therethrough and through the opening 36. The connection between the cords 39 and 40 is such that 55 all the valves are open an equal distance at one and the same time. Idler wheels 41, fixed to the top 2, insure the pull upon the valves 38 through the cords 39 being in a straight line.

60 The details of our invention may be materially modified, and we do not therefore

limit ourselves to the exact construction herein shown and described, but claim all that falls fairly within the spirit and scope of our invention.

Having described our invention, what we claim as new and desire to secure by Letters Patent, is:—

1. In a drier, the combination with a body member; of a plurality of supporting racks, 70 arranged so as to divide said body member into sections; a floor within said body member, composed in part of movable sections; a chamber or compartment below said floor; and a fan within said body member. 75

2. In a drier, the combination with a body member; of a plurality of supporting racks arranged so as to divide said body member into sections; a central core or tube between the inner ends of said racks; and fans 80 mounted within said body member, one being above and the other below said racks.

3. In a drier, the combination with a body member; of a plurality of supporting racks arranged so as to divide said body member 85 into sections; a central core or tube between the inner ends of said racks; fans mounted within said body member, one being above and the other below said racks; a floor within said body member below said racks, composed in part of movable sections; and a chamber or compartment below said floor.

4. In a drier, the combination with a body member; of a plurality of supporting racks, arranged so as to divide said body member 95 into sections; a floor within said body member, composed in part of movable sections; means, operated from the exterior of said body member for actuating said movable sections; a chamber or compartment below 100 said floor; and a fan within said body member.

5. In a drier, the combination with a body member, having an opening therethrough upon each side thereof; a closure door upon 105 each side of said body member and movably connected therewith; a plurality of supporting racks within said body member, arranged so as to divide the same into sections; fans within said body member; a floor 110 within said body member below said racks and composed of fixed strips and movable valve strips; and means, as a shiftable bar having a link connection with each of said valve strips for actuating said valve strips. 115

In testimony whereof we affix our signatures in presence of two witnesses.

ANTONIO DI DOMENICA.
ANTONINO AMICARELLI.
